UNITED STATES PATENT OFFICE.

RAY E. PARMENTER, OF LONGMEADOW, MASSACHUSETTS.

DESIGN FOR A DIRECTION INDICATOR.

Application filed November 25, 1921. Serial No. 517,793. Term of patent 7 years.

To all whom it may concern:

Be it known that I, RAY E. PARMENTER, a citizen of the United States, residing at Longmeadow, in the county of Hampden and State of Massachusetts, have invented a new, original, and ornamental Design for Direction Indicator, of which the following is a specification, reference being had to the accompanying drawing, forming part thereof.

In the drawing—

Figs. 1 and 2 are plan and elevational views respectively of a direction indicator, showing my new design.

I claim:

The ornamental design for a direction indicator, substantially as shown.

RAY E. PARMENTER.
